UNITED STATES PATENT OFFICE

153,688

DESIGN FOR A LUGGAGE CASE OR A SIMILAR ARTICLE

Leo Horwitz, Chicago, Ill.

Application May 1, 1948, Serial No. 146,117

Term of patent 7 years

(Cl. D87—5)

To all whom it may concern:

Be it known that I, Leo Horwitz, a citizen of the United States of America and a resident of Chicago, county of Cook, and State of Illinois, have invented a new, original, and ornamental Design for a Luggage Case or a Similar Article, of which the following is a specification, reference being had to the accompanying drawing, forming a part thereof.

Fig. 1 is a perspective view of a luggage case or a similar article embodying the new design;

Fig. 2 is a plan view thereof;

Fig. 3 is a side elevational view thereof;

Fig. 4 is an end elevational view thereof; and

Fig. 5 is an inverted plan view thereof.

The characteristic features of my design reside in the portions shown in full lines.

I claim:

The ornamental design for a luggage case or a similar article, as shown and described.

LEO HORWITZ.
